C. Murdoch

UNITED STATES PATENT OFFICE

HYMAN GOLDFINGER, OF BROOKLYN, NEW YORK

MOP

Application filed May 6, 1930. Serial No. 450,077.

This invention relates to improvements in mops, and more particularly to that type of device generally referred to in the trade as wet mops.

Among the principal objects which the present invention has in view are: to provide an improved mop which may be readily wrung out; to construct the mop so that it may be wrung without the user having to take hold of the mop strands; to enable the mop to be wrung out with simple mechanism forming part of the mop itself; to avoid any interference in the use of the mop by the wringing mechanism; to provide a mop in which the mop strands can be twisted for wringing purposes but will be prevented from twisting when used for mopping purposes; to obtain a flexibility between parts when the mop is being wrung and yet obtain rigidity of support for the mop strands when being used for mopping purposes; to secure simplicity of construction and operation; and to obtain other advantages and results as may be brought out in the following description.

In the drawing:

Figure 1 is an elevation of a mop embodying the invention showing the same in position ready to be wrung;

Figure 2 is a sectional view on line 2—2 of Fig. 1, showing the mop strands as they appear while being wrung; and

Figure 3 is a view similar to Fig. 2 showing the mop strands in position as they appear for mopping purposes.

In the specification:

In the specific embodiment of the invention illustrated in said drawing, the reference numeral 5 indicates the body portion in general. In this showing, the body portion provides an elongated handle 6 which is hollow for receiving a rod 7 as the core. The parts are so constructed that there is no relative rotation permitted between the handle 6 and the rod 7. It may here be stated that while I have shown the body member as comprising these separate elements of handle and rod, it is within the scope of the invention to manufacture the said body member otherwise. However, by the construc-

tion disclosed, the rod 7 provides a strong and convenient slideway and support for a wringing hand grip 8. Said hand grip 8 is adapted to both slide longitudinally upon said rod 7 and be twisted or rotated upon the rod as action requires. Said hand grip 8 has attached thereto a flaring bracket 9 projecting longitudinally therefrom toward the end of the mop away from the handle. This bracket 9 is fast with respect to said hand grip 8 so as to be revolved around the rod 7 when the hand grip 8 is rotated on said rod.

Said bracket flares toward its end away from the hand grip and has flanges at its side edges suitably perforated near the larger end of the bracket for receiving the end of a bail 10, the loop portion of which extends away from the bracket in substantial continuation thereof. The mop head or strands 11 are carried upon the looped portion of the bail 10.

At the outer end of the mop body 5, that is, at the end of said rod 7 away from the handle 6 is an end piece 12 non-rotatably secured to the rod. This end piece 12 is preferably tapered similar to the bracket 9, with the larger end thereof away from the handle end of the mop. As a result of this construction, the hand grip 8 with bracket 9 may be slid upon the end piece 12, the shape of this bracket and end piece enabling the two parts to nest with respect to each other. Adjacent the outer end of the end piece 12 is mounted a second bail 13, the loop portion of which carries the strands of the mop head 11. The construction thus described enables the mop head to be supported at its opposite ends when elongated, and yet the mop head can be doubled by sliding the hand grip 8 toward the outer end of the mop and nesting the bracket 9 upon the end piece 12. When the parts are brought to this resting position, the bails 10 and 13 will be arranged side by side and the doubled mop head 11 will be free to be used for mopping purposes.

In the construction of the end piece 12, I prefer to mount the bail 13 thereon to rotate upon an axis transverse to the axis of the rod 7. Furthermore, the end piece is provided

with outstanding ears or stops 14 at the larger end thereof in the path of rotation of the bail, thereby preventing the bail from swinging further than aligned positioned with the end piece when swinging in one direction. However, the bail can swing away from the said ears in one direction and into a position directed toward the handle end of the rod as indicated in Figures 1 and 2 whereby the tension exerted in wringing the mop will be in a proper direction for pulling away from the point of attachment of the bail to the end piece 12. Furthermore, as the bracket 9 nests upon the end piece 12, the bracket is positioned on the side of the end piece toward which the bail is otherwise free to swing, and because of this association, the bail on the bracket will at such time prevent the bail on the end piece from swinging and therefore both bails will project longitudinally side by side from the end of the body member of the mop and obtain a rigid construction by which the mop strands can be manipulated in use.

25 When it is desired to wring out the mop, the user merely slides the hand grip 8 up the rod toward the handle and in doing so, straightens out the mop head 11 to its full length. Then the hand grip 8 is twisted around the rod 7, thereby twisting the attached end of the mop head. The other end of the mop head is held by bail 13 from twisting and therefore the mop will be very readily wrung out by merely rotating the hand grip 8. The construction will obviously enable the user to use the mop without having to grasp the mop head, and yet obtain a very thorough wringing of the mop when desired. After the mop is wrung out it is very conveniently straightened out again by merely holding the hand grip with the mop head downward and it will cause a rotation of the rod and handle until the mop head is straightened out. Then the mop head can be doubled by merely sliding the hand grip 8 downward by virtue of its own weight and again nesting the bracket 9 upon the end piece 12. For convenience in manipulating the mop when wringing out the mop head, the end of the handle 6 toward the mop head is shown as enlarged or providing a hand grip 15 non-rotatably secured to the handle.

I claim:

55 A device as characterized comprising in combination with a flexible mop head, a body portion providing an elongated handle and a rod fixed with respect thereto extending axially therefrom, an enlarged end piece on the outer end of said rod, a bail pivoted to said end piece at an enlarged portion thereof so as to permit swinging the bail on an axis transverse to the axis of the rod and prevent rotation of the bail around said axis of the rod, a slideable and rotatable hand grip on the rod, said hand grip having a bracket at-

tached thereto, a second bail pivoted on said bracket on an axis transverse to the axis of said rod, said bracket and second mentioned bail being offset from the axis of the rod and thereby adapted to be brought into juxtaposition to the end piece and first mentioned bail at the end of the rod, said mop head being attached at its opposite ends to the said bails whereby the mop is doubled and the ends held adjacent to each other in the aforementioned juxtaposed position of the bails, the bail on the outer end of the body portion being adapted to swing back so as to be directed toward the slideable hand grip upon withdrawing said hand grip from the juxtaposed position of the bails, whereby the outer bail rests adjacent its supporting end piece while the mop is being wrung.
